TELEPHONE SYSTEM

George C. Reier, Westfield, and Albert Tradup,
West Englewood, N. J., assignors to Bell Telephone Laboratories, Incorporated New York, N. Y., a corporation of New York

Application June 4, 1941, Serial No. 396,510

11 Claims. (Cl. 179—27)

This invention relates to telephone systems and particularly to improved telephone apparatus and circuits for providing facilities for completing a plurality of simultaneous telephone connections between a plurality of calling lines and a single called line.

The invention has for its object to provide improved facilities whereby a single loud-speaker line circuit is rendered accessible to a plurality of calling lines so that a plurality of talking connections between a plurality of independent substations and a single loud-speaker station may be simultaneously established.

This object is attained in accordance with a feature of the invention by terminating a loud-speaker line circuit in a plurality of sets of line terminals of a connector switch, and multiplying the said connector switch terminal sets with corresponding terminal sets of other connector switches, thereby rendering the loud-speaker line circuit accessible, simultaneously, to a plurality of calling stations by way of the plurality of connector switches.

In accordance with a particular feature of the invention, the connector switch control circuit is so designed that the talking connection to the loud-speaker line circuit is completed immediately upon seizure of the loud-speaker line by the connector switch employed in setting up the connection. In other words, the usual ringing of the called line together with the ringing trip features which are required of connector switches employed in extending connections to the regular type of substation are dispensed with.

Another feature of the invention precludes the possibility of the loud-speaker at the called station "howling" or "singing" when the number of lines connected to the loud-speaker line is varied. More specifically, this feature of the invention resides in the provision of means associated with the loud-speaker line which functions to maintain a condition of balance between the network and line impedances at the terminals of a hybrid coil, included in the loud-speaker line circuit, irrespective of the number of calling lines that may be connected to the loud-speaker station.

These and other features of the invention will be readily understood from the following detailed description made with reference to the accompanying drawings in which:

Fig. 1 illustrates diagrammatically an attendant's telephone circuit and associated equipment, by means of which calls intended for a loud-speaker line circuit involving features of the

present invention, may be originated. The equipment shown in Fig. 1 is that generally found at an order turret of the type which finds extensive use in brokerage houses, department stores, airports, and other similar establishments. It is to be understood that this showing is used for illustrative purposes only, since any other type of calling station will serve equally well.

Fig. 2 is a diagrammatic representation of a connector switch, which serves to extend calls, originated at the station of Fig. 1, to the loud-speaker line circuit terminating therein; and

Fig. 3 is a circuit diagram illustrating the loud-speaker line circuit of this invention.

Before describing the operation of the system made up of Figs. 1, 2 and 3, a brief reference to the equipment illustrated in each of the figures will be made.

In Fig. 1 there is diagrammatically illustrated an order turret OT of the type which is particularly suitable for use in brokerage houses, airports, etc., and at which calls incoming from a private branch exchange may be answered by the actuation of a key individually associated with the private branch exchange line, and at which outgoing calls may be originated. The order turret equipment consists essentially of a plug ended telephone set 10; a pair of jacks 11—12 by means of which the telephone set may be connected to the attendant's key-set; a plurality of three position keys 13, 14, 15 and 16; and a telephone dial 17. The keys 14, 15 and 16 are used for talking purposes, while the key 13 is used for making the attendant's position busy. When a key is up, in the "normal" position illustrated, the line individual thereto is not in use. Moving the key to the mid or "talk" position connects the attendant's telephone set to the line, and if a key is moved down to the "hold" position, the call on the corresponding line is held and the attendant's telephone set is disconnected and may be used on some other line.

There are shown three lines 20, 22 and 23 terminating at the order turret OT. Key 16 controls the regular order turret line 20 which appears, with other order turret lines, at a private branch exchange board (not shown) and is used only to answer incoming calls. Key 14 controls an "overflow" line 22 which appears at each of a group of from five to ten order turrets. Should a call come into the private branch exchange when all the regular lines, such as line 20, to a given group of turrets are busy, the call would be connected to the "overflow" line 22 to be answered by the first attendant to become available. Key

15 at the order turret controls a regular private branch exchange extension line, such as line 23, over which an order turret clerk or attendant may place outgoing calls. The dial 17 is provided for setting up connections which require dial service. Line 23, in the system to be described in detail hereinafter, permits the attendant to call various locations or stations equipped with loud-speaking equipment, such as the station shown in Fig. 3.

The connector circuit C (Fig. 2) over which calls are extended from the order turret OT to the loud-speaker line circuit of Fig. 3, is in general, similar to well-known connector circuits which control the operation of connector switches in extending a connection to a telephone line of the regular type. It distinguishes therefrom primarily in that it is designed to omit the regular ringing and tripping features and to cut through the connection immediately upon seizure of the called line.

The loud-speaker station B (Fig. 3) consists essentially of a loud-speaking receiver 25, an associated amplifier 26 of any suitable design, a distant-talking transmitter 27, a visual signal 28, a key 30, a hybrid coil H and a plurality of balancing impedance networks 31, 32 and 33.

The loud-speaker line circuit, designated by the numeral 34 terminates in three sets of line terminals a, b and c of the connector switch C of Fig. 2. These terminals are connected in multiple with corresponding terminals of other connector switches, such as the terminals a', b' and c' of the connector schematically represented by the block C'. By virtue of the fact that the line 34 terminates in three sets of connector terminals a, b, c of connector C which are multiplied to similar terminals of other connectors, it may be seized simultaneously by three lines, such as line 23, which extend from three different order turrets of the type shown in Fig. 1. The sleeve terminal of each set of connector terminals is connected to the winding of a sleeve relay, such as relays 40, 41 and 42, which when operated, function to connect a corresponding impedance network 31, 32 or 33 to the network terminals of the hybrid coil H of the loud-speaker line 34. Thus, as the number of lines that are connected to the loud-speaker line 34 increases, the number of networks connected to the network terminals of the hybrid coil H is increased correspondingly. In this manner, a condition of balance is maintained between the line and network impedances regardless of the number of calling lines that are connected to the line 34. Loud-speaker "howling" is thus prevented.

The operation of the system disclosed in Figs. 1, 2 and 3 will now be described, and for this purpose Fig. 2 is placed to the right of Fig. 1, and Fig. 3 to the right of Fig. 2.

When the order turret OT is occupied, the telephone set 10 would be plugged into the jacks 11 and 12 in order that the attendant may be prepared to answer calls incoming to her order turret position. At jack contacts 46 therefore, ground is connected to the conductor 55 of the regular private branch exchange line 20, by way of the contacts 8 of key 13, contacts 48 of key 14, and contacts 49 of key 15. This ground serves to actuate a signal (not shown) at the private branch exchange as an indication to the operator thereat that the particular order turret OT is occupied and in readiness to receive calls. At jack contacts 50, ground is connected to the lead 51 of the "overflow" line 22 to indicate to the

private branch exchange operator that one or more turrets in a common group are being occupied. At jack contacts 53, ground is also connected to a lead which extends to a supervisor's cabinet and serves to operate a signal thereat as an indication to the supervisor that the order turret attendant's position is occupied. With the telephone set 10 in the jacks 11 and 12, the attendant's transmitter is connected to the transmitter supply battery 5. The order turret attendant is now prepared to receive incoming calls.

When the private branch exchange attendant or operator receives the indication (ground connection to lead 55 of line 20) that the order turret OT is occupied, incoming calls to the private branch exchange will then be connected to the line 20 by the private branch exchange operator when the attendant at turret OT is desired.

It will now be assumed that the operator at the private branch exchange (not shown) receives a call for an order turret attendant and extends the call to the turret OT by way of line 20. The private branch exchange operator applies ringing current to the ring conductor of line 20 which extends to the gas tube 21 by way of the conductor 47. The tube 21 ionizes in the well-known manner and starts to oscillate. This produces harmonics of the ringing current which are heard in the receiver of the attendant's telephone set 10. The path for this signaling current may be traced from ground, condenser 56, contacts 57 of key 14, conductor 58, contacts 59 and 60 of key 16, contacts 61 of key 15, ring conductor 62, right windings of coil 63, normal contacts of dial 17, tip conductor 64, contacts 65 of key 15, contacts 66 and 67 of key 16, contacts 68 of key 14, condenser 69 to ground. Since the receiver of the telephone set 10 is connected across the lower portion of the right winding of coil 63, the ringing induction is received therein and the order turret attendant recognizes it as a ringing signal.

Upon receipt of the ringing signal, the order turret attendant actuates key 16, associated with the line 20, to the "talk" position, whereupon the ringing tone is removed from the attendant's receiver and a bridge is connected across the tip and ring conductors through the retardation coil 70 and the induction coil 63. This bridge, which functions to provide an indication at the private branch exchange that the call has been answered, may be traced from the tip conductor 71 of line 20, contacts 72 and 66 of key 16, contacts 65 of key 15, conductor 64, normal contacts of dial 17, upper right winding of coil 63, retardation coil 70, conductor 62, contacts 61 of key 15, contacts 68 and 74 of key 16 to the ring conductor 75 of line 20. The turret attendant is now free to converse with the calling subscriber over line 20.

It will now be assumed that the order turret attendant is unable to furnish the information sought by the party on line 20 and finds it necessary to obtain such information from a clerk who is located at the station B (Fig. 3). Such a situation may arise, for example, at an airport or air lines terminal, when the calling party seeks information concerning ticket reservations or airplane schedules which can only be furnished by a clerk at a station such as station B.

The order turret attendant now actuates the key 16 to the "hold" position whereupon the retardation coil 71 is bridged across the line 20 to hold the connection. The connection of coil 71

across the line 20 is effected by the contacts 72, 78 and 74 of key 16. With the connection on line 20 held by means of the coil 71, the order turret attendant proceeds to establish a connection between her position and the station B over the private branch exchange extension line 23. To do this the key 15, associated with the line 23 is actuated to the talk position, whereupon the conductors 64 and 62 with which the dial 17 is associated are connected to the line 23 by way of the contacts 3 and 4 of key 15 and the normal hold position contacts 2 and 6. The attendant may now dial the designation assigned to the station B after having received the usual dial tone. It is to be understood that other automatic switches may be involved in the completion of a connection to the desired line 34, but that only the last switch, that is, the connector switch C, is illustrated in the drawings. The operation of such switches, if required, is well known and need not be incorporated in this description. It will be assumed that the connection has advanced to the connector C and it will now be described how this switch completes the connection to the line 34.

When the key 15 is operated to the "talk" position, the lead 55 to the private branch exchange line 20 is opened at the key contacts 49. This functions to provide an indication at the private branch exchange that the line 20 is no longer receptive to incoming calls. When the dial 17 is moved off-normal, the induction coil 63 and retardation coil 70 are short-circuited by the off-normal contacts of the dial and the ring side of the attendant's receiver is opened. The ring side of the attendant's receiver is opened to prevent the attendant from hearing the make and break of the dial. The dial functions in a well-known manner to effect the transmission of dial pulses which are used to control the operation of automatic switches, only the connector switch C and its control circuit being illustrated in detail in Fig. 2.

When the connector circuit (Fig. 2) is seized in the course of the completion of the connection originated at the order turret OT, relay 100 operates in a circuit extending from grounded battery, upper winding of relay 100, conductor 101, upper normal make-before-break contacts of relay 102 to the ring conductor 103, over the closed loop at the order turret OT, tip conductor 104, lower normal make-before-break contacts of relay 102, conductor 105, to ground by way of the lower winding of relay 100.

Relay 100 operated, operates relay 106 in an obvious circuit. At its middle armature and front contact, relay 106 grounds the sleeve lead 107, thus holding the preceding switches (if any) in their operated position. Relay 106 also opens the circuit to the release magnet 200 of the connector switch and prepares an operating circuit for the vertical magnet 108.

At each interruption of the dial 17, relay 100 releases, and operates the vertical magnet 108 in series with relay 109, relay 109 operating on the first interruption of the dial. The operating circuit for vertical magnet 108 may be traced from grounded battery, winding of magnet 108, winding of relay 109, contacts 110 of vertical off-normal springs VON, front contact and innermost armature of relay 106, to ground by way of the back contact and armature of relay 100. The vertical magnet 108 steps the shaft and brushes of the connector switch to the desired level in a well-known manner. Relays 106 and 109 are 75

designed to be slow in releasing and do not release on dial interruptions.

On the first step of the switch shaft, the vertical off-normal springs VON transfer the pulse circuit from the spring 111 to spring 112, but, relay 109 being operated, retains the pulse circuit through the vertical magnet 108 during the dialing of the first digit. When the impulses from relay 100 cease, relay 109 releases and transfers the pulse circuit from the vertical magnet 108 to the rotary magnet 113. This circuit may be traced from grounded battery, winding of magnet 113, armature and back contact 114 of relay 102, armature and contact 115 of relay 116, conductor 117, normal make-before-break contacts of relay 118, back contact and armature of relay 109, vertical off-normal spring 112 and its associated spring contact, front contact and innermost armature of relay 109, to ground by way of the back contact and armature of relay 109.

The next series of interruptions from the pulse relay 100 causes the rotary magnet 113 to operate in parallel with relay 120. Magnet 113 operates in the circuit traced in the preceding paragraph, and relay 120 operates in an obvious parallel branch extending from the armature contacts 114 and 115 of relays 102 and 116, respectively. Relay 120 operates on the first interruption of the dial and is made slow-to-release in order to remain operated on dial interruptions. The rotary magnet 113 steps the connector shaft and brushes around to the terminals *a* of the called line 34.

Relay 120 prepares the busy test circuit and short-circuits the normal make-before-break contacts of relay 118, through which the rotary magnet circuit is taken, so that the operation of relay 118, while the sleeve brush of the connector switch C passes over busy contacts, will not open the rotary magnet circuit.

On the completion of the dial interruptions for the last digit, relay 120, being slow in releasing, remains operated a short time after the brushes make contact with the terminals *a* of the called line 34, during which a busy test is made. On the release of relay 120 (assuming line 34 is idle), relay 116 operates through its lower winding in a circuit extending from grounded battery, winding of sleeve relay 42 (Fig. 3) associated with the called line 34, conductor 9, sleeve terminal 122 of the terminal set *a*, corresponding brush, conductor 123, inner upper armature and back contact of relay 120, conductor 124, lower winding of relay 116, conductor 125, back contact and outermost armature of relay 118 to ground at the outermost upper armature and front contact of relay 106. Relay 116 operates sufficiently to close its contacts 127, whereupon the upper winding of relay 116 is energized and the relay fully operates. At its innermost lower armature and front contact, relay 116 places a direct ground on the sleeve terminal 122 of the connector C which serves to operate the relay 42 associated with the called line 34. The same ground also places a busy condition on the sleeve terminal in the multiple bank *a'*. Relay 116 operated, opens the circuit to rotary magnet 113 at contacts 115, so as to prevent further stepping of the brushes if the calling party should again operate the dial. It also prepares a reversing circuit to relay 100.

It will be noted that when relay 116 operated to close its armature contacts 127, an obvious circuit was completed from ground to the winding of relay 130, so that relays 116 and 130 operate substantially simultaneously. In previous con-

necter circuits of the general type described, relay 130 served as a medium for completing the connection of a machine ringing current source to the called line when relay 116 operated. The path for such ringing current extended by way of an auxiliary winding of relay 130 which is generally referred to as the "trip" winding, which, when a called party answered a call, functioned to operate relay 130 to disconnect the ringing current source from the called line. In the present case, the tripping winding of relay 130 and the machine ringing current source are not required and relay 130 operates substantially simultaneously with relay 116.

In the description thus far advanced, the brushes of connector switch C have been moved into engagement with the terminals of set *a* associated with the called line 34 and relays 130 and 116 of the connector circuit and relay 42 of the called line have been operated. With relays 130 and 116 operated, the talking conductors of the connector circuit are extended to corresponding conductors of the called line by way of the tip and ring brushes and terminals of the switch. It is thus apparent that the talking connection is completed immediately upon the seizure of an idle set of line terminals by the connector switch.

It will be noted that the winding of relay 2, at the called station B is normally connected across the tip and ring conductors of the line 34. When the talking circuit is closed, due to the operation of relays 130 and 116 in the connector circuit, relay 102 operates by way of both windings over the closed loop effected by the winding of relay 2 of the called line 34. With relay 102 operated, talking battery, if the calling station were a common battery telephone, or supervisory battery in this case is supplied to calling station OT through the windings of relay 100. This battery connection may be traced from grounded battery, upper winding of relay 100, conductor 101, front contact and outermost upper armature of relay 102, contacts 202 of relay 116, to the tip conductor 104; and from ground, lower winding of relay 100, conductor 105, front contact and outermost lower armature of relay 102, front contact and outermost upper armature of relay 116 to the ring conductor 103.

At the called station B, the switch 30 would be normally operated, so that when the connection is completed to the windings of relay 102 in the connector circuit C, relay 2 would operate to actuate the lamp signal 28 in an obvious circuit. The lighted lamp 28 serves as an indication to the clerk at station B that there is a call waiting on the line 34. A path is also completed for the energization of the transmitter 27. This path extends from grounded battery, filaments of resistance lamp 203, left winding of coil 204, resistance 205, right winding of coil 204, resistance 206, front contact and left armature of relay 2, to ground by way of switch 30. The transmitter 27 is energized by the potential drop across resistance 205.

At its right armature, relay 2 opens a short circuit normally maintained across the input to the loud-speaker amplifier 26 by way of the switch 208. The switch 208 serves, as is obvious, as a volume control switch for the loud-speaker 25.

It will be noted that prior to the seizure of the line 34 by the connector switch C, the network terminals 210 and 211 of hybrid coil H are open circuited. When relay 42 operated, as a consequence of the seizure of the line 34 and the con-

sequent connection of ground to the sleeve terminal 122 of the connector C, the impedance network, schematically shown at 33, was connected across hybrid coil terminals 210 and 211 to balance the impedance of the line which is now connected to the line 34 by way of the connector C. This condition of balance insures against "howling" of the loud-speaker 25 which would otherwise occur.

10 Upon noting the lighted signal 28, the clerk at station B recognizes that his line 34 is connected to a calling line. The order turret attendant may now speak over the established connection by talking into the transmitter of his telephone set 10. As hereinbefore stated, the transmitter battery 5 serves to energize the attendant's transmitter at the order turret OT so that, when the attendant talks into the transmitter, speech frequency currents are set up in the coils 63 and are impressed upon the line comprising conductors 64 and 62. The speech transmission path extends from the conductor 64, contacts 3 and 2 of key 15, conductor 104, condenser 213, front contact and upper armature of relay 130, contacts 133 of relay 116, brush 214 and corresponding connector switch terminal of set *a*, conductor 215 of line 34, left middle winding of hybrid coil H, condenser 216, the primary of input transformer 217 of amplifier 26, lower left winding of hybrid coil H, conductor 218 of line 34, connector terminal and corresponding brush 219, contacts 132 of relay 116, lower armature and front contact of relay 130, contacts 220 of relay 116, condenser 221, conductor 103, contacts 6 and 4 of key 15 to conductor 62. The speech signals set up in the primary of transformer 217 are induced in the secondary thereof, amplified by the amplifier 26 and impressed on the loud-speaker 25 by way of the output transformer 222. Speech signals set up at station B by the use of the transmitter 27 thereat are produced in the two upper windings of hybrid coil H and, by induction, in the pairs of line and network windings. Those induced in the line windings traverse the same path just traced to the order turret OT to be reproduced in the receiver of the telephone set 10. Due to the balanced condition of the hybrid coil, as hereinbefore mentioned, the speech signals produced by the transmitter 27 are excluded from the signal transmission path extending to the loud-speaker 25.

Should it be necessary for the established connection to be held while the order turret attendant again picks up the call on the line 20, or for any other reason, this may be accomplished by actuating the key 15, at the order turret OT to the "hold" position. This operation disconnects the attendant's equipment from the line 23 and bridges the line conductors 104 and 103 with the impedance network 225. This network is designed so as to have an impedance characteristic similar to that of the transmission circuit at the attendant's station, which it replaces when the key 15 is actuated to the "hold" position. When desired, the connection to the called line 34 may again be picked up by the order turret attendant by actuating the key 15 to the "talk" position. The results of this key operation are obvious.

At the termination of conversation between the order turret attendant and the clerk at station B, the connection is released when the attendant restores the key 15 to normal position. This operation releases relay 100 in the connector circuit, whereupon relay 106 releases. Relay 106 opens the locking circuit to relay 116 which was

established at contacts 127 of relay 116. With relays 100, 106 and 127 released, the release magnet 200 is energized in a circuit extending from grounded battery, winding of release magnet 200, contacts 228 of off-normal switch VON, back contact and outermost lower armature of relay 116, back contact and lowermost armature of relay 106, to ground at the back contact and armature of relay 100. The operation of release magnet 200 allows the connector switch shaft to return to normal in the well-known manner. When the switch is returned to normal, the release magnet circuit is opened at contacts 228 of the vertical off-normal switch VON.

It will now be assumed that, while the loud-speaker line 34 is connected to the order turret OT, a second attendant, at a position equipped in a manner similar to that shown in detail, in Fig. 1, desires to converse with the clerk at station B. At the upper portion of Fig. 1 there is shown a block O'T' which is intended to represent an order turret similar to that shown at OT and at the upper portion of Fig. 2 there is indicated a block C' which is intended to represent a connector C' similar in all details to the connector C. The three sets of connector terminals a', b' and c' are associated with the connector C' and, as hereinbefore mentioned, the individual terminals thereof are multiplied with corresponding terminals of the terminal sets a, b and c of connector switch C.

As in the previous case, the second attendant would throw the key, such as key 15, to the "talk" position and proceed to dial the line 34. The connector C' functions in the same manner as does connector C, previously described. It will be noted that the sleeve terminals and hunt terminals such as 122 and 230, of each switch are tied together, and also these terminals of each line position of each switch are multiplied. Hence, when relay 116 operated, as previously described to place a direct ground on the sleeve terminal 122, this ground was also connected to the sleeve terminal 122' of switch C'.

When the connector C' functions in response to the dial at the order turret O'T', its brushes engage the first set of terminals a'. Ground on the sleeve terminal 122' of this terminal set causes relay 118 of connector C' to operate in a circuit extending from ground on the sleeve terminal 122', its corresponding brush, conductor 123, inner upper armature and front contact of relay 120, back contact and armature of rotary magnet 113, winding of relay 118 to the battery associated with the release magnet 200. (It is to be understood that the circuit just traced, as well as others to be hereinafter traced, involve relays of connector C' and that such relays are given the same designations as corresponding relays of connector switch C.) The circuit for relay 118 is completed before relay 120 has had time to release. With relay 118 released, relay 102 operates in a circuit extending from grounded battery, upper winding of relay 102, normal make-before-break contacts of relay 130, resistance 231, outer upper armature and back contact of relay 120, contacts 332 of relay 116, brush 232' and corresponding terminal 230' of terminal set a' of connector C' to ground. Relay 118 now locks under control of relay 102 and the armature contact of rotary magnet 113 to ground at the outermost armature and front contact of relay 106.

Relay 102 operated, closes a circuit for the operation of relay 120 which extends from ground-

ed battery, winding of relay 120, contacts 115 of relay 116, conductor 117, front contact and lowermost armature of relay 118, innermost lower armature and front contact of relay 102 to ground. At its front contact and inner lower armature, relay 120 operates rotary magnet 113 in parallel with itself. The operation of rotary magnet 113 steps the shaft and brushes of connector switch C' to the next set of line terminals b' and also releases relay 118. The reason for having the locking circuit for relay 118 under control of rotary magnet 113 is for the purpose of locking relay 118 until the rotary magnet is fully operated, at which time the brushes are centered on the terminals so as to prevent false operation due to the breaking of the circuit at the above terminal before the mechanism has completed a full step. Similarly, relay 102 is locked in series with resistance 236 under control of relay 118. The release of relay 118 allows the rotary magnet 113 to release.

If the sleeve terminal 240' of terminal set b' is grounded, due to the busy condition thereof, relay 118 again operates which again causes the rotary magnet 113 to operate and step the brushes to the terminals of the next set c', relay 102, holding operated through resistance 236 to ground on terminal 240'. This operation continues until an idle set of terminals is reached or the last set of terminals in a group is reached, when the circuit functions the same as described in connection with the testing of a busy line. The hunt and sleeve terminals of the last set of a group of line terminals are not strapped together.

It will be assumed that the second set of terminals b' of connector C' is found idle. In this case, relay 116 operates and is followed by the operation of relay 130. With relays 116 and 130 of connector C' operated, the talking connection between the loud-speaker line 34 and the order turret O'T' is completed. The attendant at order turret O'T' when connected to the line 34 may wait, if he should hear conversation being carried on by the clerk at station B with another attendant, or he may break in on the conversation depending on circumstances.

When the line 34 is connected to by the connector C', relay 41 operates in an obvious sleeve circuit, and in a manner similar to relay 42 hereinbefore described, connects an impedance network 32 to the network terminals 210 and 211 of the hybrid coil H.

If the connector terminal set b' had been found busy, the connector C' would automatically advance to the next set c' and relay 40 would function to connect the impedance network 31 in parallel with the networks 32 and 33. Thus, for each calling line that is connected to the loud-speaker line 34, a corresponding impedance network is connected to network terminals 210 and 211 of the hybrid coil H to preserve the necessary condition of impedance balance and therefore, to prevent "howling" or "singing" of the loud-speaker 25.

Should all the terminal sets a', b' and c' be found busy, relay 102 would release on the release of relay 118, it being understood that the sleeve and hunt terminals of the last set c' of a group of line terminals are not strapped together. The ground from the sleeve terminal of the terminal set c' would again operate relay 118 before relay 120 releases. On the release of relay 120, relay 118 is locked operated in a circuit extending from grounded battery, winding of

release magnet 203, winding of relay 116, armature and back contact of magnet 113, normal make-before-break contacts of relay 120, front contact and uppermost armature of relay 118, to ground at the uppermost armature and front contact of relay 106. With relay 118 operated the interrupter 275 causes a busy tone to be supplied to the calling station over the tip conductor 104, by way of the innermost upper armature and back contact of relay 102 and condenser 213. The circuit remains in this condition until the call is abandoned at the calling station.

As long as there is a calling line connected to the loud-speaker line 34, relay 2 will be operated and lamp signal 28 lighted. When there is no calling line connected to the line 34, relay 2 will be deenergized, as will be also the lamp 28 and transmitter 21. Also, when relay 2 is unoperated, the input to amplifier 26 is short-circuited.

What is claimed is:

1. In a telephone system, a loud-speaker line, a hybrid coil included therein having a pair of network terminals, an impedance network, an automatic switch having a set of terminals corresponding to said loud-speaker line, a calling station, means at said calling station for causing said automatic switch to seize the terminal set corresponding to said loud-speaker line, means immediately responsive to the seizure of said terminal set by said switch for completing a talking connection between said calling station and said loud-speaker line, and means also responsive to the seizure of said terminal set by said switch for connecting said impedance network to the network terminals of said hybrid coil.

2. In a telephone system, a loud-speaker line, a hybrid coil included therein having a pair of network terminals, an impedance network, an automatic switch having a set of terminals corresponding to said loud-speaker line, a calling station, means controlled from said calling station for causing said automatic switch to complete a talking connection between said calling station and said loud-speaker line by way of the terminal set corresponding thereto, and relay means responsive to the completion of a connection between the calling station and the loud-speaker line for connecting said impedance network to the network terminals of said hybrid coil.

3. In a telephone system, a loud-speaker line, a hybrid coil included therein having a pair of network terminals, an impedance network, an automatic switch having a set of tip, ring and sleeve terminals connected to corresponding leads of said loud-speaker line, means at said calling station for causing said automatic switch to seize the tip, ring and sleeve terminals connected to corresponding leads of said loud-speaker line, means automatically responsive to the seizure of said terminals by said switch for completing a talking connection between said calling station and said loud-speaker line, and means controlled over the sleeve lead of said loud-speaker line when said terminals are seized by said switch for connecting said impedance network to the network terminals of said hybrid coil.

4. In a telephone system, a loud-speaker line, a hybrid coil included therein and having a pair of network terminals, a plurality of impedance networks, a plurality of automatic switches each having a plurality of sets of terminals corresponding to said loud-speaker line, calling stations, means at one of said stations for causing one of said automatic switches to seize said loud-

speaker line by way of one of its sets of terminals, means at another of said stations for causing another of said automatic switches to seize said loud-speaker line by way of one of its sets of terminals, and means responsive to the seizure of said loud-speaker line by each of said automatic switches for connecting a different one of said impedance networks to the network terminals of said hybrid coil.

5. In a telephone system, a loud-speaker line, a hybrid coil included therein and having a pair of network terminals, a plurality of impedance networks, a plurality of automatic switches, a plurality of calling stations, means at said stations for operating said switches to cause them to seize said loud-speaker line, means responsive to the seizure of said loud-speaker line by each of said switches for automatically completing a talking connection between said loud-speaker line and each of said calling stations, and means also responsive to the seizure of said loud-speaker line by each of said switches for connecting an impedance network to the network terminals of said hybrid coil.

20 6. In a telephone system, a loud-speaker line, a hybrid coil included therein and having a pair of network terminals, a plurality of stations, an impedance network corresponding to each of said stations, means controlled from said stations for completing separate concurrent connections between said loud-speaker line and each of said stations, and means responsive to the connection of each of said stations with said loud-speaker line for connecting the corresponding impedance network to the network terminals of said hybrid coil.

25 7. In a telephone system, a loud-speaker line connected to a first calling line by way of an automatic switch and having an impedance network corresponding to the calling line associated therewith, a second calling line, a second automatic switch, an impedance network corresponding to said second calling line, means controlled from said second calling line and including said second automatic switch for completing a talking connection between said loud-speaker line and said second calling line while said loud-speaker line is connected to said first calling line, and means effective incident to the connection of said second calling line to said loud-speaker line for connecting the impedance network corresponding to the second calling line in parallel with the impedance network corresponding to the first calling line.

30 8. In a telephone system, a loud-speaker line, a hybrid coil included in said line and having a pair of network terminals, a plurality of calling lines, means including automatic switches for establishing simultaneous connections between said loud-speaker line and all of said calling lines, an impedance network for each calling line, and means effective incident to the connection of said loud-speaker line to each of said calling lines for connecting a corresponding impedance network to the network terminals of said hybrid coil.

35 9. In a telephone system, a plurality of stations, a first and a second automatic switch, a loud-speaker line terminating in a plurality of multiple sets of terminals of each of said switches, a talking connection completed between one of said stations and said loud-speaker line by way of a set of terminals of said first switch, means effective incident to the completion of said connection for busying a correspond-

ing set of terminals of said second switch, means at another of said stations for causing said second switch to engage the bussed set of terminals thereof, means responsive to the engagement of the bussed set of terminals of said second switch for automatically stepping said second switch to the next set of terminals thereof, means responsive to the seizure of the said next set of terminals by said second switch for automatically completing a second talking connection between said loud-speaker line and said other calling station, and means responsive to the completion of each of said connections for altering the impedance characteristic of said loud-speaker line.

10. In a telephone system, a loud-speaker line, a first automatic switch, a second automatic switch, each of said switches having a plurality of sets of terminals in which said loud-speaker line terminates, each set of terminals of one switch being connected in multiple with a corresponding set of terminals of the other switch, a first calling station, a second calling station, means at said first station for causing a connection to be completed to said loud-speaker line by way of a set of terminals of said first automatic switch, means at said second calling station for causing said second automatic switch to engage said loud-speaker line by way of a set of terminals multiplied with the terminal set of said first automatic switch by way of which a connection to said loud-speaker line from said first calling station is completed, means responsive to such seizure for causing said second switch to automatically step to a second set of terminals to complete a connection between said loud-speaker line and said second calling station, and means responsive to the completion of each connection to the loud-speaker line for altering the impedance of said line.

11. In a telephone system, a loud-speaker line 40

having a tip conductor, a ring conductor and a plurality of sleeve conductors, a hybrid coil included in said loud-speaker line and having a pair of network terminals, a plurality of automatic switches each having a plurality of line positions assigned to said loud-speaker line and each position including tip, ring and sleeve terminals, the tip and ring terminals of all positions of all of said switches being connected in multiple to the tip and ring conductors of said loud-speaker line and the sleeve terminals of corresponding positions of said switches being connected in multiple with a separate sleeve conductor of said loud-speaker line, a relay included in each sleeve conductor of said loud-speaker line, an impedance network for each relay, a plurality of calling stations, means controlled from one of said stations for causing one of said switches to seize said loud-speaker line 15 by way of the tip, ring and sleeve terminals at one line position of said one of said switches, means controlled from the other of said stations for causing other of said switches to seize said loud-speaker line by way of the tip, ring and sleeve terminals at other line positions of said other switches, means responsive to the seizure of the tip and ring terminals at each line position by its respective switch for automatically completing a talking connection between the loud-speaker line and the calling station from which the switch is controlled, means responsive to the seizure of the sleeve terminals at said line positions by each of said switches for operating the corresponding sleeve relay, and means controlled by each relay for connecting a separate impedance network to the network terminals of said hybrid coil.

GEORGE C. REIER.
